UNITED STATES PATENT OFFICE.

CHRISTOPHER C. BAGNELL, OF DULUTH, MINNESOTA.

ELECTRIC SIGNAL-SWITCH.

1,396,088.

Specification of Letters Patent.

Patented Nov. 8, 1921.

Application filed April 22, 1921. Serial No. 463,717.

To all whom it may concern:

Be it known that I, CHRISTOPHER C. BAGNELL, a citizen of the United States, residing at Duluth, in the county of St. Louis 5 and State of Minnesota, have invented certain new and useful Improvements in Electric Signal-Switches, of which the following is a specification, reference being had therein to the accompanying drawing.

10 This invention relates to electric railway signal switches and has special reference to that class of switch which is operated by the wheels of a car passing over the railway track, and which class of switches 15 are operatively associated with an electric circuit for ringing a bell or flashing a light at a grade crossing of the railway track.

The principal object of the invention is to provide a simple, practical and reliable 20 switch of this type which will be positively closed at every engagement with the wheel traveling in one direction, but which will fail to close when engaged by a wheel traveling in the opposite direction.

25 Other objects and advantages of the peculiar structure will appear in the further description of the invention:

Referring to the accompanying drawing forming part of this application in which 30 like reference characters indicate like parts:

Figure 1 is a perspective view of one of my improved switches showing its coöperative relation to a rail and with the switch box cover removed, and

35 Fig. 2 is an end elevation of the box, showing the rail in section and a fragmental portion of a wheel mounted upon the rail.

1 represents a rectangularly shaped containing box in which the switch mechanism 40 is mounted and the box is designed to be permanently installed in an inclined position against the rail with suitable adjustable holding brackets 12 engaging the ties 13 of the track, as clearly shown in the drawing.

45 Within this box is installed a common knife blade switch 16, having the ordinary electric connections therewith, the blade of which is shown at 2. Upon the free end of the blade 2 is attached a vertically disposed 50 insulated head member 8, the lower end of which is engaged upon the free end of the leaf spring 3, the stationary end of which spring is suitably mounted as at 17, so as to normally hold the head 8 of the blade 2 in 55 its uppermost open position. A suitable

stop or pin 18 is provided to govern the uppermost extreme position of the spring 3, and a like pin or stop 19 is provided above the knife 2 of the switch to similarly regulate its uppermost position.

Upon the inner upper corner of the box 1, and formed integral therewith, is an upwardly extending flange portion 14 which butts against the under side of the bulb of the rail 15, thus spacing the top of the box 60 slightly below the bulb of the rail. Through the top of the box, substantially centrally thereof, is formed a rectangularly shaped opening 20, through which extends the upper end of the plunger 4, which is somewhat 65 smaller in width than the opening 20 is in length, so that it may rock back and forth in said opening. This plunger is mounted upon a pin 5 within the box and such mounting comprises a vertically slotted hole 6 in 70 which the pin 5 is engaged, thus permitting of the plunger operating both vertically and rockably. The plunger is held normally in its uppermost vertical position by a leaf 75 spring 7, similar to the spring 3 and mounted within the box in much the same manner, and the lower end of the plunger being square and resting upon the flat spring whose uppermost position is substantially 80 horizontal, will tend to keep the plunger in 85 a vertical position.

Now as a common wheel, such as indicated at 10, traverses the rail 15 in the direction shown by the arrow in Fig. 1, it is apparent that the flange 9 of said wheel will engage 90 the upper end of the plunger 4 and force it downwardly in the slot in the upper face of the box, and the plunger, being so positioned above the head 8 of the switch as to be directly over same when in its vertical position, when thus thrust downwardly by the wheel, the lower corner of same will become engaged with the upper end of the head 8 and force the blade of the switch downwardly with it, thus closing the switch. 95 This closing of the electric circuit will occur every time a wheel flange engages the plunger 4 and the latter will return to its disengaged position by the action of the spring 7, simultaneously with a like return 100 to open position of the knife blade switch by the action of the spring 3.

Now in the event of a wheel traversing the rail 15 in the opposite direction to that shown by the arrow in Fig. 1 it is apparent 110

that the flange of the wheel will engage the upper end of the plunger 4 in a like manner to that when the wheel was traveling in the opposite direction, but the opening 20 being 5 larger than the plunger 4 and such excess of space in the opening being on that side of the plunger toward the switch, the engagement of the wheel with the upper end of the plunger will tend to first tip it over before 10 depressing same when it will assume the position shown in dotted lines at 11 in Fig. 1 of the drawing. When thus depressed the lower end of the plunger will entirely escape contact with the head 8 of the switch blade 15 and fail to operate same. It is to be understood that the switch will be so positioned in relation to the rail and the place where the signal is required, that the proper functioning of the signal will occur when the wheels 20 of whatever the vehicle may be is traveling in the proper direction.

Having thus described my invention, what I claim and desire to secure by Letters Patent, is:

25 1. A railway signal switch comprising in combination with a rail, a box permanently mounted adjacent the rail, a vertically operative knife blade switch within the box, means for normally holding the blade of the switch in open position, a vertically reciprocal plunger above the switch, means for normally holding the plunger in vertical position out of engagement with the switch and means whereby when the plunger is operated by a wheel traversing the rail in one direction it will close the switch, but when 30 35

engaged by a wheel traveling in the opposite direction it will fail to close the switch.

2. In a signal switch of the class described comprising a suitable housing, a knife blade switch within the housing, means for holding the blade of the switch normally open, a vertically reciprocal pivoted plunger above the free end of the blade of the switch, means for holding the plunger upright and disengaged from the blade of the switch, whereby when the plunger is operated when in such position, it will engage the blade of the switch, and means whereby the plunger may be inclined in position and operated without engaging the switch, substantially as and for the purpose described.

3. The combination with a railway rail upon which wheels having flanges thereupon travel, of a signaling device comprising a normally opened knife switch and one piece vertically reciprocal means co-operatively associated with the switch and directly engageable by the flanges of said wheels and means whereby the reciprocal means when 55 engaged by the flange of a wheel traveling in one direction will operate the switch, but when engaged by the flange of a wheel traveling in the opposite direction will not operate the switch.

In testimony whereof I hereunto affix my signature in the presence of two witnesses.

CHRISTOPHER C. BAGNELL.
